COMPRESSOR

William G. Pontis, William A. Chryst, Carl H. Kindl, and Bayard D. Kunkle, Dayton, Ohio, assignors, by mesne assignments, to General Motors Corporation, Detroit, Mich., a corporation of Delaware

Application November 30, 1931, Serial No. 577,986
Renewed November 25, 1935

21 Claims. (Cl. 230—177)

This invention relates to improvements in motor compressors of the sealed unit type.

By "sealed unit type" is meant a device in which the compressor prime mover and the medium to be circulated are contained within a sealed housing.

It is among the objects of the present invention to provide a sealed unit motor compressor of simple structure and design, compact, and capable of operating quietly and without substantial vibration.

A further object of the present invention is to provide a lubricating system for the moving parts of the device, which system is so constructed and arranged that no appreciable amount of lubricant is discharged with the outflowing compressed medium.

These objects are attained by providing the combination of a stator, an armature, a cylinder contained within the armature, a piston, a shaft supporting the armature and the cylinder, and means for reciprocating the piston in response to the movement of the rotor.

Further objects and advantages of the present invention will be apparent from the following description, reference being had to the accompanying drawings wherein a preferred embodiment of one form of the present invention is clearly shown.

30 In the drawings:

Fig. 1 is a front elevation of the motor compressor having a horizontal shaft, and is shown in a smaller scale than the other figures.

Fig. 2 is a cross sectional view of the motor compressor in an idle state, and is taken on the line 2—2 of Fig. 1.

Fig. 3 is a fragmentary sectional view of the motor compressor, and is taken on the line 3—3 of Fig. 2.

40 Fig. 4 is a fragmentary sectional view taken on the line 4—4 of Fig. 2 and is submitted for the purpose of emphasizing the unloading valves.

Fig. 5 is a fragmentary sectional view taken on the line 5—5 of Fig. 2 and is submitted for the purpose of emphasizing the discharge valves.

Fig. 6 is a fragmentary sectional view taken on the line 6—6 of Fig. 8.

Figs. 7, 8, and 9 are fragmentary sectional views through the piston and cylinder, showing different relative positions thereof.

50 Fig. 10 is a fragmentary sectional view taken on the line 10—10 of Fig. 5, and is drawn to an enlarged scale.

Fig. 11 is a fragmentary sectional view taken 55 on line 11—11 of Fig. 10.

Fig. 12 shows the cross section through a modified form of compressor having a vertical shaft.

Referring to the drawings the numeral 20 designates a housing comprising a cylindrical wall 21 and an end wall 22. The end wall 22 extends 5 somewhat into the cylinder formed by the wall 21 and has a reverse curve 29 near its mid-portion. Both walls are provided with spaced ribs 23 and 24 for cooling and reinforcing purposes. A cover plate 25 is provided for the housing, said 10 plate having a machined surface 27 to engage the housing. Ribs 26 are formed on the cover for cooling and reinforcement purposes. A counterbore 28 in the edge of the housing receives the machined part of the cover plate. The plate 15 is secured to the housing by a clamping ring 30 which has openings 32 for receiving screw-studs 34, which in turn are threadedly received by the housing. To insure a gas tight seal between the cover 25 and the housing, a gasket 36 is provided, said gasket being of any suitable material 20 adapted to be pressed between the cover and housing.

Bosses 40 are provided on the housing, said 25 bosses having provisions for the attachment of suitable shock or vibration absorbing pads 42.

The electrical equipment of the present device comprises a stator, having laminations 50, secured together and anchored within the housing in any suitable manner. In the drawings the 30 stator is shown press-fitted into the housing. The numeral 55 designates pins or rivets for holding the laminations clamped together between outside plates 53 and 54. A rotor, having laminations 56 which are held clamped between 35 plates 57 and 58 by pins or rivets 59, is supported on a part of the compressor as will be described.

The terminals of the stator windings are connected to lead-in plugs 60 of any suitable design. The plugs in the present instance are 40 hermetically secured in openings provided in the housing, said plugs having provisions on the outside of the housing for the attachment of the power lines.

The end wall 22 of the housing has a recess 45 66 in its interior surface, said recess being substantially concentric of the cylindrical wall of the housing. The end cover 25 has a similar recess 67 substantially in coaxial alignment with recess 66. A shaft 62 having concentric end portions 63 and 64 and an eccentric portion 65 has its one end 63 press-fitted into the recess 67 of cover plate 25, so that a gas tight fit obtains. The end 63 of the shaft is spaced from the bottom surface of the recess 67, forming chamber 55

67a. Cover plate 25 has an interiorly threaded passage leading into said chamber 67a and receives a lead-in pipe 86 as shown in Fig. 2. The other end 64 of shaft 62 fits snugly into the recess 66 so that the shaft is non-rotatably supported between cover 25 and end wall 22.

A cylinder block 70, comprising a cylindrical middle portion 71 and diametrically smaller end portions 72 and 75, is rotatably supported upon the concentric portions of the shaft 62. One end of block 70 engages a machined surface 68 on the inner side of the end wall 22, the other end of the block engaging the finished surface 173a of end cover 25, thus preventing endwise movement 15 of the block relative to the shaft. A transverse bore 73 is provided in the block 70 so that its axis intersects the axis of the shaft 62 at substantially right angles. A cylinder head 74 in the form of a ring is press fitted over the middle 20 portion of the block 70, thereby hermetically closing both ends of the cylindrical transverse bore 73 in said block. The rotor laminations 56 are press fitted upon the cylinder head 74. This secures the block 70 to the rotor laminations, 25 thereby making the cylinder block a part of the rotor of the electric machine.

The chamber formed by the cylinder bore 73 in the block 70 and the cylinder head ring 74 has a piston 78 therein, forming compression 30 chambers A and B. For purposes of description double acting piston 78 has two head portions, the faces thereof being designated by the numerals 84 and 85, the former forming one wall of compression chamber A, the latter of compression chamber B. Piston 78 has a rectangular, transverse opening 79 through which the shaft 62 extends. Specifically the eccentric portion 65 of the shaft is positioned within the confines of said piston opening. The dimension of 40 the said opening 79 transversely of the piston is longer than the dimension thereof longitudinally of the piston. The piston head portion having face 84 has a passage 101 leading from said face into the opening 79 in the piston. A similar passage 102 is provided in the piston portion having face 85. To prevent rotative movements of the piston within the cylinder, a pin 84a is press-fitted into the block 70 and extends into a longitudinal slot 85a in the surface 45 of the piston, the slot being of sufficient length to permit ample longitudinal movements of said piston.

The piston, carried within the block 70 which is rotated about shaft 62 due to the fact that block 70 forms a part of the rotor of the electric machine, is therefore also rotated about the eccentric portion 65 of shaft 62. To translate this relative rotative motion of the piston and shaft into a reciprocatory movement of the 50 piston, a cross head 77 is interposed between the piston and the eccentric portion 65 of the shaft. This cross head is a rectangular block 77 fitting upon said eccentric portion of the shaft and within the transverse opening 79 in the piston. The longer or transverse surfaces of the piston opening 79 slidably support the block 70, however, the shorter or longitudinal surfaces of the piston opening 79 are spaced a greater distance than the corresponding surfaces of block 77, 55 thereby providing the space between these block and opening surfaces and thus permitting the block 77 to move in the piston opening transversely of the piston.

The eccentric portion 65 of shaft 62 has a peripheral groove 91 of predetermined length.

This groove has a channel opening therethrough, which channel communicates with a longitudinal duct or passage 90 in the shaft 62, which passage leads in the chamber 67a in end cover 25 as shown in Fig. 2. Cross head 77 has openings 93 and 94 provided in diametrically opposite sides respectively, these openings or channels 93 and 94 providing communication between passages 101 and 102 and the peripheral groove 91 in proper recurrent intervals as will 10 be described later. Due to the latter fact, the cross head has to maintain its relative position transversely of the piston which at all times maintains its relative position to the piston. For this purpose, pins 95 and 96, press fitted into the 15 piston 78 provide fingers 97 and 98, respectively, which have the cross head 77 interposed therebetween.

Within the chamber 67a there is provided a 20 check valve 87 which permits fluid to flow from pipe 86 into the channel 90 under proper circumstances, but which will prevent a return flow of fluid under all circumstances.

Preferably this valve comprises a disc 87, urged upon an annular valve seat formed by a ridge 25 88 on the bottom wall of recess 67. A spring 89 yieldingly urges the disc 87 upon its seat.

The cylinder head ring 74 has ports 107 providing for the discharge of fluid from the respective compression chambers into the housing. 30 For purposes of preventing a back flow of compressed fluid into the compression chambers, particularly when the respective piston ends are traveling on their suction strokes check valves 103 and 104 have been provided in the cylinder 35 head ring 74. These discharge valve mechanisms are constructed in the following manner, and due to the fact that both compression chambers are provided with similar discharge valves, only one will be described for the sake of brevity. 40

Adjacent the compression chamber A the cylinder head ring 74 is provided with an annular recess 105 in its outer surface, the bottom of said recess having an annular ridge 106, providing a seat for the disc valve 103, as clearly shown 45 in Figs. 10 and 11. Ports 107, arranged in a circular, row preferably on one side of its center, provide for communication between the compression chamber A and the compression side of the valve 103. Another recess 110 cuts into the 50 recess 105 and opens into the housing. A tubular member 109 is press-fitted upon the cylinder head ring 74, thereby covering the recesses 105 and 110. A blade spring 112 secured at one end to member 109 by a rivet 113 has its free end 55 engaging the disc valve 103, yieldingly urging it against its seat 106.

A baffle plate 181 is attached to the inner surface 173a of cover plate 25, so that a space is provided between the baffle plate and end cover, 60 this space being properly located so that the discharged fluid will engage the cover plate for cooling purposes. The baffle plate has a flared extension 182 defining an opening into which the cylindrical member 109 extends. From this, it 65 may be seen that annular member 109 not only supports the discharge valve spring 112, but it also acts as a deflector, directing the discharged fluid from ports 107 into the flared end of the baffle plate 181 and thence into the cooling space 70 between said baffle and end cover. In the present construction baffle plate 181 is attached directly to the interior surface of the cover plate, a cut-away 185 in said cover plate forming the 75 cooling space. An opening 191 in a lug 190 on

the cover plate leads from the cooling space into a pipe 192 received by the threaded portion of said opening 191.

The aforescribed construction provides for a flow of fluid from any suitable source through pipe 86 into the chamber 67a after valve 87 has been moved from its seat by fluid pressure. From the chamber 67a the fluid flows through the shaft channel 90 and the passage leading 10 into the peripheral groove 91. From groove 91 the fluid enters one or the other of the passages 93 and 94, dependent upon the relative position of the cross head 77 to shaft 62. If the fluid enters passage 93, then it proceeds through the piston passage 101 into the compression chamber A, as the surface 84 of the piston moves away from the piston head ring 74. Upon reversal of this piston movement the communication between passages 93 and groove 91 is cut off and naturally the fluid in the compression chamber A will have pressure exerted thereupon, which, when sufficient, will force the fluid through ports 107 to move valve 103 from its seat, the fluid then proceeding through recess 110 along the inner surface 108 of baffle ring 109 into the flared portion 182 of the baffle plate 181. Now the fluid enters the cooling space 185 between the baffle 181 and end cover 25 from whence said fluid will flow through opening 191 and pipe 192 to the desired device which is connected with pipe 192.

If on the other hand passages 94 and 102 are in communication with the groove 91, then the fluid flow is directed through the following path 94, 102, chamber B, ports 107 of said chamber, past valve 104 into chamber 117, thence into the cooling space 185.

A feature of this invention resides in the fact that the cross head 77 not only acts as a driving medium between the eccentric portion 65 of shaft 62 and the piston 78, but it also functions as a distributing valve for the fluid flow into the proper compression chambers. As a distributing valve it operates in the following manner.

Referring to Figs. 3, 7 to 9 and at present particularly to Fig. 3, the piston is shown in its lower dead center position, considering chamber B the bottom chamber. Here the piston completely occupies the chamber B so that chamber A is at maximum capacity. In this position of the piston, passage 93 of the cross head is in full communication with the peripheral groove 91, which under all conditions is the fluid supply groove. Passage 94 of the cross head is entirely cut off from communication with the supply groove.

The passage 93 of the cross head aligns with the piston passage 101, thus fluid from the supply groove 91 may flow through passages 93 and 101 into the compression chamber A. Communication between passages 91 and 93 was not effected until the piston had been rotated by the cross head through a part of its cycle, thus piston 78, or more specifically its head surface 84 had been moved away from head ring 74 a predetermined distance to establish a vacuum in chamber A before passage 93 started communication with the supply groove 91.

In Fig. 7, the piston surface 85 has been moved away from the cylinder head ring 74 and has just started to form the chamber B. It will be seen that passage 94 is in communication with the supply groove 91, the other passage 93 being entirely cut off therefrom.

Fig. 8 shows the piston midway between the cylinder heads. Chamber A is still cut off from

the supply groove 91, while chamber B is still receiving a fluid supply therefrom.

In Fig. 9 the piston is shown in a position in which it has practically finished its compression stroke as regards to chamber A, while chamber B is substantially charged to full capacity and ready to have the fluid therein compressed. Now port 94 will be moved out of register with the supply groove 91 and passage 93 will be moved into fluid intake relation therewith.

From the aforesaid it may be seen that while one compression chamber is being charged with fluid, the fluid in the opposite chamber is having pressure exerted thereupon, and thus, due to this concurrent loading and discharging of fluid a substantially constant flow of fluid under pressure into the housing is obtained.

To facilitate the starting of a compressor and particularly under load such as a back pressure, it is desirable to provide a device, which for a period will permit the prime mover to operate substantially free of said load. In the present instance applicant has provided a centrifugal unloading device which circulates the fluid flow so that, as one side of the piston discharges its fluid under pressure into the housing, the fluid pressure in the housing will be introduced into the opposite cylinder to assist the piston in its movement to compress the fluid in the first mentioned chamber.

Each cylinder chamber has such a centrifugal unloading device, and because both of these are alike, only one of them will be described detailedly. A recess 123 is provided in block 70 alongside the cylinder bore 73 in the block. A passage 149 in the block 70 leads from the interior of the housing into this recess. Another opening 147 in the block connects the compression chamber A with the recess 123. A cup-shaped member 125 is press-fitted into said recess, a head portion on the cup-shaped member closing the recess adjacent the cylinder head ring 74. In the head portion of the cup-shaped member there is provided a central passage 127, leading into the interior of the recess 123, said passage communicating with a duct 145 which leads to the opening 147. An opening in the side wall of the cup-shaped member aligns with passage 149, thus connecting the interior of the housing with the interior of the cup-shaped member. A weight member 131, centrally recessed as at 135 is slidably carried within the cup-shaped member. A valve pin 137, having a tapered end, has one end of a spring 141 engaging it, the other end of said spring is seated in a recess in the interior surface of the head of the cup-shaped member. Valve pin 137 is substantially in coaxial alignment with the passage 127. Spring 141 yieldably urges the valve pin 137 into the bottom of the recess 135 of the weight block 131, thereby maintaining its tapered end in spaced relation with the passage 127.

The parts of the unloading device for compression chamber B correspond to the parts of the unloading device for chamber A as follows: 124 like 123; 150 like 149; 148 like 147; 126 like 125; 128 and 146 like 127 and 145, respectively; 132 like 131; 138 and 142 like 137 and 141, respectively; and 136 like 135.

These unloading devices operate as follows. Assuming that a pressure exists within the housing 20, and it is desired to start the compressor, the circuit through the electric machine is then closed, causing rotation of the rotor and consequently of the cylinder block 70 which forms a

part of the rotor. As has been described before, rotation of the block 10 causes reciprocation of the piston, which reciprocation results in pressure being exerted upon the fluid taken into the 5 compression chambers. Ordinarily this fluid discharge into a chamber having a fluid pressure therein would tend to stall the motor. This is prevented, for one compression chamber is in communication with the interior of the housing 10 10 20 through passages 147, 145, 127, and 149, the other through passages 148, 146, 128, and 150. If chamber A is discharging fluid under pressure through the aforementioned ducts or passages into the housing, then the housing is exerting 15 15 pressure into the chamber B through its respective passages, and consequently a counter-balance of pressures on opposite sides of the piston obtains, thereby providing a substantially free acting piston. The motor may accelerate to a predetermined speed substantially without load. 20 The said predetermined speed having been attained, the weight members 131 and 132 will be thrown outwardly toward the closed end of the respective cup-shaped members 125 and 126, thus 25 25 the respective valve pins 137 and 138 will be moved to close the passages 127 and 128 respectively, and thereby the chambers A and B are completely shut off from communication with the interior of the housing through their respective 30 30 pressure relieving passages.

The necessary lubricating system for the device will now be described; referring more particularly to Figs. 1 to 3, the motor housing 20 provides a supply of lubricant 161. A nipple 162 is threaded with one end into a boss 163 of the motor housing 20 and with its other end into an elbow 164, which also threadedly receives a second vertically directed nipple 165. A cap 165a is threaded upon the nipple 165 and prevents lubricant in the housing 20 from being discharged. The length of the nipple 165 is such that when the oil reaches a proper level in the housing, the nipple 165 will overflow.

The cover 25 provides a lug 166, interiorly recessed to receive a pivot member 167 for rotatably supporting a gear 168, preferably made from bakelite or like material, to eliminate noise while cooperating with a gear ring 169, press-fitted upon a reduced portion 170 of the cylinder block 10. This gear ring 169 which is to drive the lubricant conveying gear 168 is held against lateral movement by inter-position between the adjacent end of the cylinder block 10 and the bottom 171 of an annular recess 172 in the end cover 25. The gear 168 is received within an annular recess 173 and its inner face is flush with the finished surface 173a of the cover 25. A retainer plate 174, preferably screwed on the inner surface 173a of the cover 25 as at 175, retains the gear 168 in position and also obstructs the passage of lubricant from the oil carrying tooth spaces into the motor housing. A groove 176 in the bottom 171 of the annular recess 172 receives the lubricant lifted by the gear 168. A longitudinal groove 177 in the outer surface of shaft 62 transports the lubricant from groove 176 to the piston opening 79. The oil then passes through the piston opening 79. A longitudinal groove 178 at the opposite end of the shaft conveys this lubricant from the piston opening 79 to radial grooves 179 in the end of the cylinder block 10 adjacent the end wall 22 of the housing. The inwardly extending portion of the end wall 22 and the reverse curve 29 provide a means and act as a baffle for preventing the lubricant from

being thrown against the windings, and cause the lubricant to pass over the end wall 22 and be cooled in returning to the housing.

Some of the oil will naturally leak into the compression chambers and intermix with the fluid therein and be discharged therewith into the housing. As has been mentioned before, baffle ring 109 directs substantially all of the discharged fluid into the cooling space 185. As this lubricant containing fluid strikes the substantially cool end cover 25 and baffle plate 181, the lubricant in the fluid will be condensed. The condensed oil will flow to the lubricant supply, thereby passing through a depression 182a in the baffle plate 181. 5 10 15 20 25

The fluid discharged from the housing is therefore comparatively free of oil vapor. This is a very desirable feature of this as well as of all compressors, since otherwise oil vapor, carried by the discharged fluid would condense along the 20 inner wall of the discharge pipe 192 and settle therein, forming oil mud. In the space of time this oil mud would accumulate to such an extent that it would finally obstruct the free passage of compressed fluid through the pipe 192. 25

In Fig. 12 a modified form of compressor is shown. In this device shaft 211, corresponding to shaft 62 of the main construction, is so supported and arranged in the housing 202 so that the rotor is adapted to rotate in a vertical position. The modified compressor, disclosed in Fig. 12 is practically of the same construction as the one described. Thus the prime mover and the operating parts of the modified form of compressor are substantially identical to the respective parts of the main construction, only the oiling system and the cooling baffle necessitating essential constructive changes which will be dealt with now.

In this construction the end wall 201 of the 40 housing, which now forms the bottom thereof has an annular extension 206 coaxially of the rotor, this extension being recessed to receive the end 210 of shaft 211. A plate 205, centrally recessed, is press-fitted upon the annular extension 206. 45 The inner edge of said extension and the surface of the plate 205 which is substantially flush with said edge provide an end thrust bearing for the cylinder block 204. The lower end of the cylinder block has an annular cut-away portion, 50 which together with the plate 205 and the inner surface of the cylinder head ring 74 forms an annular chamber 213. The cylinder head ring has a spiral groove 215 in its outer, peripheral surface adjacent the lower end thereof. The 55 chamber 213 is in communication with the lowest convolution 214 of the spiral groove 215 through a plurality of ducts 216 in the cylinder head ring. A radial groove 207 is cut in the inner surface of the end wall 201 and connects the convolution 214 60 of the spiral groove 215 with a recess 208 in the central portion of plate 205. The recess 208 is in communication with a longitudinal groove 209, provided in the outer surface of the shaft portion 210. Passage 209 leads directly to the piston 65 opening 19. Lubricant from the lubricant supply within the housing must pass through an annular filter 224 comprising an annular screen 222 fitting over an annular extension 223 within the housing, said screen being covered by any suitable filtering material 224. After passing through the filter, the oil enters a duct 212 in the end wall 70 of the housing, said duct leading into the annular chamber 213. The lubricant, having entered chamber 213, will be ejected through openings 75

or ports 216 by a centrifugal force, entering the convolution 214 of the spiral groove 215 under pressure. The characteristic of the spiral groove 215 is such that it will force said lubricant downwardly into the radial groove 207, from whence the lubricant is forced through recess 208 and longitudinal channel 209 into the cross head containing piston opening 79. From this opening the fluid will pass through a longitudinal channel 209a in the upper end of the shaft 211. From this channel the lubricant will enter radial grooves 216 and 217, formed in the upper end of the cylinder block 204, and is then thrown out onto a plate 218 rotating with the rotor. The plate 218 extends over and beyond the edge of the inner opening in the baffle plate 220, which is secured to the cover plate 25 of the housing by screws 220a, so that the lubricant on plate 218 is thrown upon the baffle plate 220 from which it drops into the main lubricant supply. To pass the rotor on its way from baffle plate 220 to the lubricant supply, the lubricant flows through passages 221 formed by recesses in the annular wall of the housing. In passing along the recesses 221 of the ribbed annular wall, the lubricant is cooled whereby the main lubricant supply is maintained at a substantial proper temperature. A lug 227 of the housing 202 provides a threaded hole 226 wherein a nipple 225 is received, said nipple also being threaded into an elbow 228. Another nipple 229 is also threadedly received by the elbow 228. Lubricant may be poured into the housing from the outside through nipple 229, elbow 228 and nipple 225. A cap 230 threaded upon the nipple 229 prevents oil in the housing from being discharged.

The baffle ring 235 is slightly flared as clearly shown in Fig. 12. This is for the purpose of utilizing centrifugal force to transport the condensed oil on the interior surface of said baffle ring, which was mixed with the discharged compressed fluid in the form of oil vapor. When the condensed oil reaches the upper edge of said baffle ring it will be thrown onto the cooling baffle 220 and follow the already described course of the circulating lubricant.

While the form of embodiment of the present invention constitutes a preferred form, it is to be understood that other forms might be adopted, all coming within the scope of the present invention.

What is claimed is as follows:

1. In a motor compressor, the combination of a sealed housing; a stator; a rotor; a cylinder block having a cylinder bore therein carried within the rotor; a shaft having concentric and eccentric portions, the cylinder block being rotatably carried by the concentric portion of the shaft; a double acting piston in said cylinder bore forming compression chambers therein, said piston engaging the eccentric shaft portion and being reciprocated thereby in response to rotation of the cylinder about said shaft; ducts provided in the piston and shaft and cooperating to introduce a fluid medium into the compression chambers; openings in the chambers having valve seats formed on one side thereof; and spring-loaded valves yieldingly urged against said seats and operated at a predetermined pressure to provide communication between the sealed housing and the compression chambers.

2. In a motor compressor, the combination of a sealed housing; a stator; a rotor; a cylinder block having a cylinder bore therein carried within the rotor; a shaft having concentric and eccentric

portions, the cylinder being rotatably carried by the concentric portion of the shaft; a double acting piston in said cylinder bore forming compression chambers therein, said piston engaging the eccentric shaft portion and being reciprocated thereby in response to rotation of the cylinder about said shaft; ducts provided in the piston and shaft, and cooperating to introduce a fluid medium into the compression chambers; a check valve in one of said ducts adapted to admit fluid into the compression chambers in response to a predetermined pressure thereon; valved ports opening out of the chambers for the discharge of the compressed fluid from said compression chambers, said check valve and ducts admitting fluid to one of said chambers while one of said valved ports permits the discharge of compressed fluid from another chamber into said housing.

3. In a motor compressor, the combination of a sealed housing adapted to carry fluid under pressure; a stator; a rotor; a cylinder block; a cylinder head forming a piston chamber in said block; a double acting piston in said chamber forming compression chambers therein; a shaft having an eccentric portion operatively connected with said piston to operate it in response to rotation of the cylinder block upon said shaft; channels in the shaft and the piston adapted to be aligned to provide a fluid flow into the piston chambers; outlet ports in the cylinder head; valves for said channels and ports; ducts connecting the compression chambers with the interior of the sealed housing; and means adapted to close said ducts in response to a predetermined rotary speed of the cylinder block.

4. In a motor compressor unit, the combination of a sealed housing; a stator; a rotor; a cylinder block carried by the rotor said block having a transverse bore; a cylinder head on the block closing the ends of said bore to form a piston chamber; a double acting piston in said chamber forming compression chambers therein; a shaft having an eccentric portion operatively connected with said piston to reciprocate it in response to rotation of the cylinder block upon said shaft; channels in the shaft and piston adapted to introduce fluid into the piston chambers; outlet ports in the cylinder head; valves for said channels and ports, and centrifugal means normally connecting the cylinder chambers and adapted at a predetermined speed to discontinue the said connection.

5. In a motor compressor, the combination of a sealed housing adapted to carry fluid under pressure and containing; a stator; a rotor; a cylinder block supported within the rotor; a head for closing the cylinder block; a double acting piston in the cylinder block forming compression chambers therein; a shaft having an eccentric portion for rotatably supporting said piston and operating it in response to rotation of the cylinder block upon said shaft; channels in the shaft and piston for introducing fluid into the compression chambers; outlet ports in the cylinder head; valves for said channels and ports; ducts connecting the compression chambers with the interior of the sealed housing; and centrifugal means normally, yieldably urged to maintain connection between the cylinder chambers and housing and adapted at a predetermined speed to discontinue the said connection.

6. In a motor compressor, the combination of a sealed housing adapted to carry compressed fluid and containing; a stator; a rotor; a block

carried within the rotor and providing a cylinder; a cylinder head ring on said block; a double acting piston in said cylinder forming compression chambers therein; a stationary shaft 5 ably supporting the cylinder block and piston and having means for reciprocating the piston within the cylinder in response to rotation of the block; channels in the shaft and piston adapted to cooperate to direct fluid into the compression chambers; outlet ports in the cylinder head; check valves for said channels and ports; ducts connecting the compression chambers with the interior of the sealed housing; and centrifugal means normally, yieldably urged to maintain said 10 ducts open and adapted at a predetermined speed to close said ducts.

7. In a motor compressor, the combination comprising, a housing; a cylinder block having recesses and a cylinder bore therein; a cylinder head forming a piston chamber in said block; a double acting piston in said bore forming compression chambers therein; a shaft for rotatably supporting the cylinder block, said shaft having an eccentric portion for drivingly engaging the 20 piston; means for causing relative rotation between the shaft and the cylinder block, whereby the piston is caused to slide within the chamber; a low pressure fluid supply; means actuated in response to relative rotation between the cylinder 25 block and the shaft for providing communication between said fluid supply and the cylinder chamber; pressure responsive valves carried by the cylinder block for discharging compressed fluid from the compression chambers; means providing 30 direct fluid communication between said compression chambers and valves mounted in said recesses for rendering the last mentioned means ineffective when a predetermined rotary speed of the cylinder block is reached, said valves including, weight members slidably mounted within 35 said recesses so as to be moved by centrifugal force, valve pins actuated by said weight members, and springs for resisting the centrifugal force on said weight members and valve pins.

45 8. In a motor compressor, the combination comprising, a housing; a cylinder block having recesses and a cylinder bore therein; a cylinder head forming a piston chamber in said block; a double acting piston in said bore forming compression chambers therein; a shaft for rotatably supporting the cylinder block, said shaft having an eccentric portion for drivingly engaging the piston; means for causing relative rotation between the shaft and the cylinder block, whereby 50 the piston is caused to slide within the chamber; a low pressure fluid supply; means actuated in response to relative rotation between the cylinder block and the shaft for providing communication between said fluid supply and the cylinder 55 chamber; pressure responsive valves carried by the cylinder block for discharging compressed fluid from the compression chambers; means providing direct fluid communication between said compression chambers and valves mounted in said recesses for rendering the last mentioned means ineffective when a predetermined rotary speed of the cylinder block is reached, said valves including, centrally recessed weight members 60 slidably mounted within said recesses so as to be moved by centrifugal force, valve pins mounted in the central recesses in said weight members and adapted to be actuated thereby, and springs for resisting the centrifugal force on said weight members.

70 9. In a motor compressor, the combination

comprising, a housing; a cylinder block having recesses and a cylinder bore therein; a cylinder head forming a piston chamber in said block; a double acting piston in said bore forming compression chambers therein; a shaft for rotatably 5 supporting the cylinder block, said shaft having an eccentric portion for drivingly engaging the piston; means for causing relative rotation between the shaft and the cylinder block, whereby the piston is caused to slide within the chamber; a low pressure fluid supply; means actuated in response to relative rotation between the cylinder block and the shaft for providing communication between said fluid supply and the cylinder chamber; pressure responsive valves carried by 10 the cylinder block for discharging compressed fluid from the compression chambers; means providing direct fluid communication between said compression chambers and valves mounted in said recesses for rendering the last mentioned means 15 ineffective when a predetermined rotary speed of the cylinder block is reached, said valves including, cup-shaped members press fitted into said recesses and each having a central passage 20 therein, weight members slidable within said cup-shaped members and moved therein by centrifugal force, valve pins actuated by said weight members 25 and adapted to close said central passages, and springs urging said weight members to resist the centrifugal force on said weight members. 30

10. In a motor compressor, the combination comprising, a sealed housing; a cylinder block having recesses and a cylinder bore therein; a cylinder head forming a piston chamber in said block; a double acting piston in said bore forming compression chambers therein; a shaft for rotatably supporting the cylinder block within 35 said housing, said shaft having an eccentric portion for drivingly engaging the piston; means for causing relative rotation between the shaft and the cylinder block, whereby the piston is caused to slide within the chamber; a low pressure fluid supply; means actuated in response to relative rotation between the cylinder block and the shaft for providing communication between 40 said fluid supply and the compression chambers; pressure responsive valves carried by the cylinder block for discharging compressed fluid from the compression chambers into said housing; and means for relieving the pressure on the end surfaces of said double acting piston until a predetermined operating speed is reached. 45

11. In a motor compressor, the combination comprising, a sealed housing; a cylinder block having recesses and a cylinder bore therein; a cylinder head forming a piston chamber in said block; a double acting piston in said bore forming compression chambers therein; a shaft for rotatably supporting the cylinder block within 50 said housing, said shaft having an eccentric portion for drivingly engaging the piston; means for causing relative rotation between the shaft and the cylinder block, whereby the piston is caused to slide within the chamber; a low pressure fluid supply; means actuated in response to relative rotation between the cylinder block and the shaft for providing communication between said fluid supply and the compression chambers; pressure responsive valves carried by the cylinder block for discharging compressed fluid from the compression chambers into said housing; and means for equalizing the pressure on the end surfaces of said double acting piston until a predetermined operating speed is reached. 55

12. In a motor compressor, the combination

comprising, a sealed housing; a cylinder block having recesses and a cylinder bore therein; a cylinder head forming a piston chamber in said block; a double acting piston in said bore forming compression chambers therein; a shaft for rotatably supporting the cylinder block within said housing, said shaft having an eccentric portion for drivingly engaging the piston; means for causing relative rotation between the shaft and the cylinder block, whereby the piston is caused to slide within the chamber; a low pressure fluid supply; means actuated in response to relative rotation between the cylinder block and the shaft for providing communication between said fluid supply and the compression chambers; pressure responsive valves carried by the cylinder block for discharging compressed fluid from the compression chambers into said housing; and means for admitting fluid from within said sealed housing to the end surfaces of said double acting piston until a predetermined operating speed is reached.

13. In a motor compressor for compressing a fluid medium, the combination comprising, a rotary cylinder block having a cylinder bore and recesses therein; cup-shaped members press fitted into said recesses, said cup-shaped members each having a passage in the end thereof; means providing communication for said medium from said cylinder bore through said passages to the outside of said cylinder block; weight members slideable in said cup-shaped members and moved therein by centrifugal force; valves actuated by said weight members and adapted to close said passages; and springs for opposing the centrifugal force, and urging said valves away from said passages.

14. In a motor compressor, an unloading valve for reducing the load on the motor at start, and comprising in combination, a cup-shaped member having a passage therein; a weight member having a recess therein and slideable within said cup-shaped member; a valve pin having a head thereon and disposed within said recess, said pin being movable with said weight member to close said passage; and a spring interposed between said head and said cup-shaped member.

15. In a motor compressor, the combination comprising, a sealed housing having lubricant and fluid cooling surfaces; a cylinder block having a cylinder bore therein; a cylinder head forming a piston chamber in said block; a piston in said bore forming a compression chamber therein; a shaft for rotatably supporting the cylinder block, said shaft having an eccentric portion for drivingly engaging the piston; means for causing relative rotation between the shaft and the cylinder block, whereby the piston is caused to slide within the chamber; a low pressure fluid supply; means including said shaft and piston for intermittently providing communication between said fluid supply and said compression chamber; a lubricant supply in said housing; means also including said shaft for providing a communicating passage for said lubricant from said supply to said piston; means providing a return passage for said lubricant over a cooling surface; valves for controlling the discharge of compressed fluid from said compression chambers to within said housing; and a baffle cooperating with said valves and within said housing for causing the discharged fluid to contact the cooling surfaces.

16. In a motor compressor, the combination comprising, a sealed housing having lubricant and fluid cooling surfaces; a cylinder block having a cylinder bore therein; a cylinder head form-

ing a piston chamber in said block; a piston in said bore forming a compression chamber therein; a shaft for rotatably supporting the cylinder block, said shaft having an eccentric portion for drivingly engaging the piston; means for causing relative rotation between the shaft and the cylinder block, whereby the piston is caused to slide within the chamber; a low pressure fluid supply; means including said shaft and piston for intermittently providing communication between said fluid supply and said compression chamber; a lubricant supply in said housing; means also including said shaft for providing a communicating passage for said lubricant from said supply to said piston; means providing a return passage for said lubricant over a cooling surface; valves for controlling the discharge of compressed fluid from said compression chambers to within said housing; baffles cooperating with said valves and within said housing for causing the discharged fluid to contact the cooling surfaces, said baffles comprising an annular member mounted on said cylinder head and a baffle plate surrounding a portion of said annular member and attached to said housing and spaced therefrom.

17. In a motor compressor having a sealed housing, a shaft supported by said housing, a rotor, a cylinder block within said rotor and having a cylinder bore therein, a stator within said housing surrounding said rotor and having windings thereon, and a piston mounted in said bore and having an opening therein, a lubricating system comprising in combination, a lubricant supply chamber formed by said housing; communicating passages for the lubricant flow to and from said opening; a lubricant conveyor carried by said housing and adapted to convey lubricant to one of said passages; said opening providing a lubricant supply chamber for said piston; means communicating with another of said passages for returning the lubricant to said supply chamber; and means cooperating with said last mentioned means for preventing said lubricant from being thrown against the windings.

18. In a motor compressor, a rotor assembly adapted to be mounted on a stationary shaft having a fluid conducting opening therein, comprising, in combination, a substantially cylindrical cylinder block having an axially extending shaft opening and a transversely extending cylinder bore therein; a piston in said cylinder bore having an opening therethru through which the shaft extends, said piston also having fluid conducting openings therethru; a member within the first mentioned opening in said piston for drivingly connecting the shaft and piston, said member having fluid conducting openings therein for intermittently establishing fluid communication between the opening in said shaft and those in said piston; a sleeve member fitted over said block to provide a cylinder head and forming compression chambers at each end of said piston, said sleeve having fluid outlet openings therein communicating with said compression chambers; a second sleeve secured to said sleeve member and providing a fluid baffle for deflecting the flow of fluid from the compression chambers; spring urged valves for controlling the discharge of fluid from the compression chambers; and a motor rotor surrounding said sleeve member and drivingly secured thereto.

19. A compressor unit having a casing enclosing a body of oil and into which the high pressure fluid is discharged and having a flat plate wall, a rotating discharge part of said compressor

in said casing rotating adjacent to and on an axis perpendicular to said wall, an outlet from the casing in said wall thereof, and a flat baffle parallel to said wall and surrounding said rotating part and having a surface adjacent said outlet, 5 said rotating discharge part of said compressor discharging into the space between said flat plate wall and said baffle.

20. A motor-compressor unit including a substantially cylindrical casing having an end wall, 10 an outlet in said end wall, a baffle in front of said end wall and having a circular opening, a compressor within said casing having a rotating discharge part extending into said circular opening.

21. A motor-compressor unit including a cylindrical casing having a flat end wall, an outlet in said end wall, a flat stationary baffle adjacent said outlet and having a circular opening, a compressing unit within said casing, a motor within 5 said casing drivingly connected to said compressing unit, said compressing unit having a rotating discharge part extending into said circular opening.
